DESIGN FOR A STOVE LEG

Mary E. Brown, Alvarado, Tex.

Application November 14, 1941, Serial No. 104,144

Term of patent 3½ years

To all whom it may concern:

Be it known that I, Mary E. Brown, a citizen of the United States and resident of Alvarado, in the county of Johnson, in the State of Texas, have invented a new, original, and ornamental Design for a Stove Leg, of which the following is a specification, reference being had to the accompanying drawing, forming a part thereof.

Figure 1 is a front elevational, Figure 2 is a side elevational, Figure 3 is a rear elevational, and Figure 4 is a top plan view, of a stove leg, showing my design.

I claim:

The ornamental design for a stove leg, as shown.

MARY E. BROWN.
